UNITED STATES PATENT OFFICE

135,307

DESIGN FOR A VACUUM TUBE

William W. Eitel, San Bruno, and Jack A. McCullough, Millbrae, Calif., assignors to Eitel-McCullough, Inc., San Bruno, Calif., a corporation of California

Application June 30, 1942, Serial No. 107,373

Term of patent 14 years

To all whom it may concern:

Be it known that we, William W. Eitel and Jack A. McCullough, citizens of the United States of America, and residents, respectively, of San Bruno and Millbrae, county of San Mateo, State of California, have invented a new, original, and ornamental Design for a Vacuum Tube, of which the following is a specification, reference being had to the accompanying drawing, forming part thereof.

Referring to the drawing, the figure is a perspective view of a vacuum tube, showing our new design.

We claim:

The ornamental design for a vacuum tube, substantially as shown.

WILLIAM W. EITEL.
JACK A. McCULLOUGH.
